INVENTOR

Sylvronia A. Reed,

BY

William Porter,

ATTORNEY

UNITED STATES PATENT OFFICE.

SYLVANUS A. REED, OF NEW YORK, N. Y., ASSIGNOR TO THE REED PROPELLER CO., INC., OF NEW YORK, N. Y., A CORPORATION OF NEW YORK.

AERONAUTICAL PROPELLER.

Original application filed June 22, 1922, Serial No. 570,139. Divided and this application filed December 2, 1924. Serial No. 753,483.

This invention relates generally to propellers for aeronautical use and particularly to propellers of the metal type, including such as those which I have described and claimed in my U. S. Letters Patent No. 1,463,556, dated July 31, 1923, and also in my application for patent, Serial No. 570,139, filed June 22, 1922, and this application is a division of said application Serial No. 570,139, which issued as Patent No. 1,518,410, on Dec. 9, 1924.

A general object of the invention is to provide a metal propeller structure which can be mounted in driving relation with the drive-shaft, without weakening the propeller structure. Another object of the invention is to provide mounting means with increased resisting strength against the stress of the propeller in its operation. The invention also includes means for mounting the propeller in abutting relation to the end of the drive-shaft, so that the weakening effect of a shaft-receiving orifice in the propeller structure is avoided. There are other important advantages resulting from the use of my improvements, which will appear from the description hereinafter given.

Certain forms of my improved propeller and certain preferred methods of constructing the same are hereinafter described and set forth and illustrated in the drawings, wherein:

Figure 1, is a broadside view of a metal propeller embodying one form of my invention.

Figure 2, shows the same propeller as that in Fig. 1, with the view at right-angles thereto, and the propeller mounted on the end of a drive-shaft projecting from a fuselage.

Figure 3, shows a modified form of the propeller and the mounting means which is spaced away slightly therefrom.

Figure 4, shows a propeller like that in Figs. 1 and 2, with a modified form of mounting means for the drive-shaft.

Figure 5, is a cross-sectional view of the

mounting means shown in Fig. 4, and shows the drive-shaft fuselage in side view.

Referring to the drawings, in the various forms herein shown, the shaft attaching means is such that I am able to dispense with the central orifice in the propeller for the reception of the shaft, and in Figs. 4 and 5, the structure is one in which there are no bolt-holes in the propeller which thus remains intact and without any openings therein.

In Figs. 1, 2, 4 and 5, I show a construction of the propeller in which a virtual twist in the central part 7-8, for bringing the sections at those points to the required angle with the plane of rotation, which is accomplished by a compound bend at 18-19, and 20-21, these bends being in opposite directions and at angles 18 with 19, and 20 with 21, and each extending entirely across the propeller and the pair 18-19, being symmetrical with the pair 20-21. There are various combinations of bends that will accomplish the same purpose, but I prefer that substantially of the type illustrated, wherein the plate-like character of the central part 22, affords a wide surface which will accommodate the wide face of the attaching flange, and which is especially convenient and efficient for securing the propeller in operative position to its seat or attaching flange. In this form, the portion of the blades 7-5, and 8-6, has the same twist, contour, edges and dimensions as in the other form, and there is likewise preferably a continuation of the leading edge of each blade with the trailing edge of the other.

In Figs. 1 and 2, the central flat section 22, of the propeller, is provided with a centrally located circular row of bolt-holes 27, and is engaged upon one side by the flat surface of a solid flange 28, which is integral with the drive-shaft 11, shown as projecting from the end of the fuselage 29. This attaching flange 28, is a solid metal disk except for a circular row of bolt-holes,

formed therein in correspondence with those of the propeller indicated at 27, for the reception of the attaching bolts 31, which pass through the two parts and hold them in fixed relation.

In Fig. 3, substantially the same structure is shown as that in Figs. 1 and 2, except that the propeller has the helical central section, instead of the flat section 22, and the solid attaching flange 32, which is integral with the drive-shaft 11, is shaped or bent to conform to the curved surface of the central portion of the propeller with which it makes close contact, the bolts 33, being employed to unite the parts as shown.

In Figs. 4 and 5, the drive-shaft is provided at its ends with an integral attaching flange or head 34, formed of a solid piece of metal with its outer face provided with a transverse seat or depression in which is snugly fitted the flat central section 22, of the propeller, which is securely held therein by means of a transverse clamping member or bar 36, which is detachably secured to the head or flange 34, by means of bolts 37. As the propeller is securely seated between the ribs or sides of the depression, the latter serve as abutments for receiving the stress of the propeller when rotated.

It is evident that in none of the arrangements described herein, is the attaching means required to reinforce the twist or bend in the propeller, but functions merely as an attaching means to the drive-shaft embracing the latter over sufficient distance to allow adequate attachment. The twist or bend of the metal or other material imparted during manufacture of the propeller, for the purpose of giving the blades the appropriate inner or hub angles necessary for helical or similar twist, perpetuates itself during all the stresses of protracted operation in flying, solely by its inherent elastic rigidity or set, at the angles, bends or curves imparted during manufacture or intentional adjustment. In order that such constancy of shape under stress may exist there must be a relation between the thickness and the width of the material and its elastic limit and other physical properties to insure constancy at the rate of rotation, thrust and other conditions specified by the particular flight duty for which the propeller is planned. By my construction of the entire propeller from a plate which need not exceed one inch in thickness, at the thickest part, I am able to obtain effective thrust at points comparatively close to the axis of rotation, say for example, nine or twelve inches therefrom, and I thus add materially to the aggregate efficiency of propellers.

In the form of my propeller in which the central blade connecting portion is made flat and without bends or twists therein, as indi-

cated at 22, this flat portion provides an efficient and simple structure for mounting the propeller in place. In one form of the invention a flange mounted on the end of the drive-shaft forms a seat to which the propeller is bolted through a series of small openings. In another form the propeller is clamped between holding plates that are connected at the margins of the propeller, which is left wholly imperforate so that its maximum strength is retained. While the constructions referred to produce a continuation of the leading edge of one blade with the trailing edge of the other the invention is not limited to this relation of parts.

I wish to be understood as not limiting my invention to the particular forms herein shown and described, as it is manifest that various modifications may be made in the different parts, without, however, departing from the spirit of my invention.

Having thus described my invention, what I claim and desire to secure by Letters Patent, is:—

1. In aeronautical propeller construction, said propeller having a central blade-connecting part formed imperforate at the axis of rotation, and central abutting drive-shaft attaching means having said blade-connecting part countersunk and secured therein.

2. In aeronautical propeller construction, a substantially flat central attaching part having suitably bent metal blades attached thereto, a drive-shaft, connecting means between said attaching part and said shaft and comprising lateral abutments for engaging the edges of said attaching part.

3. In aeronautical propeller construction, a substantially flat central attaching part having suitably formed blades attached thereto, a drive-shaft, connecting means between said attaching part and said drive-shaft and comprising lateral abutments against which the edges of said part bears, and a holding member for securing said part in fixed relation with the connecting means.

4. In aeronautical propeller construction, said propeller having a central blade-connecting part formed plate-like and imperforate at the axis of rotation, and drive-shaft attaching means comprising a member provided with a wide face for engaging said plate-like portion of said central part and having oppositely arranged marginal abutments engaging the edges of said central part, and means for securing said part to said member.

5. In aeronautical propeller construction, a single-piece propeller made from a relatively thin plate of metal with blades having their outer portions tapering in width and thickness to the tips and with an imperforate central part at the axis of rotation, drive-shaft attaching means having an abutting

end-flange to which the central part of said drive-shaft attaching means having an abutting end-flange to which the central part of 10 propeller is attached face-on.

6. In aeronautical propeller construction, a single-piece propeller made from a relatively thin plate of metal with blades having their outer portions tapering in width and thickness to the tips and with an imperforate central part at the axis of rotation, said propeller is attached face-on, said abutting flange having upset parts embracing said central-part of the propeller, and a holding-member attached to the upset parts for securing the propeller to said flange.

SYLVANUS A. REED.
